CYLINDER-HEAD.

1,374,079.

Specification of Letters Patent.

Patented Apr. 5, 1921.

Application filed February 26, 1919. Serial No. 279,380.

To all whom it may concern:

Be it known that I, WILHELM HEFTI, citizen of the Republic of Switzerland, residing at Wülfingen, Switzerland, have invented 5 the following-described Improvements in Cylinder-Heads.

The invention concerns the construction of internal combustion engines and apparatus subject to like thermal conditions and 10 provides certain principles of cylinder head structure as herein described which effectually eliminate the occurrence of strains from thermal expansions and abrupt temperature differences in the walls thereof and thereby 15 maintain the strength and integrity of the head under all conditions.

The preferred form of the invention is shown in the drawings:

20 Figure 1 being an axial section and Fig. 2 a plan with the valve cage removed.

The cylinder proper comprises an inner cylinder wall or liner 1 seated on a shoulder on the outer cylinder wall 2 and therewith forming the usual water jacket space. In 25 the present case the two cylinder walls are arranged with their end faces substantially flush, this being a preferred but not necessary relation. The cylinder head comprises an inner head wall 3 forming the end in- 30 closure to the cylinder space and therefore directly exposed to the temperature therein, an outer head wall 4, a peripheral side wall 5 of circular section and a central valve-socket wall 6 also of circular section. The 35 two circular walls constitute the sole connection between the inner and outer head walls, 3 and 4, forming therewith a hollow head structure adapted for the circulation of a cooling medium and which can be read- 40 ily made of a single casting and with walls of uniform thickness. Appropriate open- 45 ings not shown, are provided for the entrance and exit of the cooling water which may circulate freely in the annular space around the socket wall 6. All the valve 50 mechanism which is desired to be mounted in the head structure is situated in the valve-socket so that between said socket and the periphery there is an annular portion of each head wall uninterrupted by passages

and hence free to expand on thermal change, uniformly along every radius. The cavity of the socket in the present case, accommodates a fuel injection valve 7 and an air starting valve 8 both contained in a suitable 55 valve cage 9 indicated diagrammatically in the drawing.

The inner head wall 3 which is slightly dished is of no greater diameter than just sufficient to span and make a proper joint 60 with the end face of the cylinder liner 1, with which transverse surface the joint is made in the present case by means of a circular rib 10 which seats on a gasket held in the packing groove 11 in the liner. The 65 said rib and groove are both disposed as close to the interior cylindrical surface of the liner as consistent with security and inasmuch as the rib is in the nature of a peripheral flange on head wall 3, there is no 70 peripheral metal in the head outside the joint which is liable to thermal expansion at a different rate from the central portion of such wall; that is to say, the said inner head wall terminates at the joint, close to 75 the interior cylindrical space, and does not extend beyond it, in consequence of which practically the whole area of said head wall 3 is exposed on one side to the temperature of the combustion space and on the other to 80 that of the cooling water, no part of the wall or head structure being in contact with, or in heat-transferring relation to, the metal of the cylinder outside the joint, as for example, at the surface marked 12. At any 85 given moment therefore there is equality of temperature at all points of said wall and hence an absence of temperature difference likely to develop thermal strains. If the head wall 3 were extended over the surface 90 12, as is commonly the case, the metal in such extended peripheral portion would be subjected to a different temperature and by shrinking or expanding at a different rate from the symmetrical interior part of the 95 wall would thereby set up strains tending to crack or weaken the metal. The absence of such peripheral metal and the symmetry of the head wall as above described coöperate to eliminate all these strains thereby in- 100

suring the integrity of the casting under all conditions and preserving at all times a leak tight joint with the cylinder.

5 The inner head wall 3 in order to form a combustion space of the most desirable shape slopes from the neighborhood of the joint away from the piston so as to present a dished or concave face to the interior of the cylinder.

10 From the peripheral packing rib 10, the side wall 5 extends divergently outward to its point of junction with the outer head wall 4, at which point it is provided with a bolt flange 13 or equivalent attachment means 15 adapted for engagement by the bolts or studs 14 by which the head is secured in place. Such bolts are threaded to the outer cylinder wall 2 substantially in the transverse plane of the joint groove 11 and extend free from 20 that plane to the flange 13 thereby leaving a space around the joint which is open to atmosphere. The divergence of the side wall 5 brings the bolt flange 13 into proper alignment with the bolts and the cylinder wall 2 25 and also provides an ample capacity of interior water space which is specially desirable when the valve-socket contains several valves. The divergent angle of the side wall is also effective in directly transmitting the 30 clamping pressure of the bolts 14 to the joint groove 11 which pressure, it will be observed, also set the liner firmly upon the shoulder of the outer cylinder wall. The divergent shape of the head structure and the details of this and the liner joint and the connecting 35 means are important features of the invention but are manifestly subordinate to the symmetrical disposition of metal of the head walls and the elimination of abrupt temperature differences, the relation of which has 40 now been explained, and no limitation is to be understood as applying to this invention in respect to such or other incidental features except as definitely mentioned in the 45 following claims.

Claims:

1. The combination with a cylinder, of a 50 water-jacketed head structure symmetrically formed about a central space or cavity which accommodates all the cylinder-head valve mechanism, the inner head wall making a joint against a transverse surface of the cylinder and being devoid of peripheral metal outside the joint capable of developing thermal strains in said structure.

55 2. The combination with a cylinder, of a water-jacketed head comprising a single central valve socket containing all the cylinder-head valve mechanism and an inner head 60 wall making joint with a transverse surface of the cylinder and attachment means on the head, removed from said joint, for connecting the head to the cylinder.

65 3. The combination with a cylinder, of a removable head making joint with the end

face of the cylinder near the interior surface thereof and being devoid of peripheral metal outside the joint capable of developing thermal strains in the head structure, and connection members extending from the region 70 of said joint to the outer end of the head structure.

4. The combination with an outer cylinder wall having a liner seated thereon and forming a water-jacket space therewith, of a removable water-jacketed head making joint with the liner and being devoid of peripheral metal outside the joint capable of developing thermal strains in the head structure and connection members extending 75 from the outer cylinder wall in the region of said joint to the outer end of the head structure.

5. The combination with a cylinder, of a water-jacketed cylinder head comprising 80 inner and outer head walls united solely by a single valve-socket wall and a peripheral side wall, the inner head wall making joint with the cylinder end and being devoid of peripheral metal outside the joint capable of 85 developing thermal strains in the structure.

6. The combination with a cylinder, of a water-jacketed cylinder head structure comprising an inner head wall making joint with the cylinder end and a peripheral side 90 wall extending divergently from said joint toward the outer wall of said head structure.

7. The combination with an outer cylindrical wall and a liner seated thereon, of a water-jacketed head comprising an inner 100 head wall making joint with the liner, a peripheral side wall diverging from the joint, a bolt flange near the wide part of the side wall, and means for securing the flange to the outer cylinder wall.

105 8. The combination with a cylinder, of a water-jacketed cylinder head comprising inner and outer head walls united solely by a single valve-socket wall and a peripheral side wall, the inner head wall making joint 110 with the cylinder end, being devoid of peripheral metal outside the joint capable of developing thermal strains in the structure, and sloping from the neighborhood of the joint away from the piston so as to present 115 a dished or concave face to the interior of the cylinder.

9. The combination with a cylinder, of a water-jacketed head structure symmetrically formed about a central space or cavity which 120 accommodates all the cylinder - head valve mechanism, the inner head wall being dished or concave toward the interior of the cylinder, making a joint against a transverse surface of the cylinder and being devoid of peripheral metal outside the joint capable of developing thermal strains in said structure.

125 10. The combination with an outer cylinder wall having a liner seated thereon and forming a water-jacket space therewith, of a 130

removable water-jacketed head making joint with the liner and being devoid of peripheral metal outside the joint capable of developing thermal strains in the head structure, the seat of the joint with the liner being in substantially the same plane as the end of the cylinder wall, and connection

members extending from the outer cylinder wall in the region of said joint to the outer end of the head structure.

10

In testimony whereof, I have signed this specification.

WILHELM HEFTI.
